United States Patent Office.

PETER LOW, OF CLEVELAND, OHIO.

Letters Patent No. 67,560, dated August 6, 1867.

IMPROVEMENT IN COOKING-STOVES.

The Schedule referred to in these Letters Patent and making part of the same.

TO ALL WHOM IT MAY CONCERN:

Be it known that I, PETER LOW, of Cleveland, in the State of Ohio, have invented certain new and useful Improvements in Cooking-Stoves; and I hereby declare that the following is a true, full, and exact description of the same, reference being had to the accompanying drawings, and to the letters of reference marked thereon. In the drawings annexed, which make a part of this specification—

Figure 1 exhibits a side-view of my stove.

Figure 2 is a front elevation of the same.

Figure 3 is a front view of the ribbed back piece of the fire-box.

The letter A represents the body of the stove open at the two sides to get access to the baking-chamber, and otherwise constructed similar to cooking-stoves in common use. B represents the grate with which the fire-box is furnished. The bars of the grate are constructed at their inner end with a convex metal rim, t, perforated with a double series of holes, s, running lengthwise of the rim, and also with a number of lateral ribs, the object of these ribs being to prevent the coal from coming in contact with holes s, and thus to prevent the admission of air from beneath the grate. At the back of the fire-box is placed the adjustable plate C, furnished with vertical ribs, with a series of holes between them. Behind the plate C is the partition D, against which the plate C rests. The said partition has a hollow rim, e, at top, with a number of holes in it, through which the air can have passage into the fire-box, and is also supplied with vertical ribs n, the said ribs being intended to prevent plate C from pressing against the partition D, and thus preventing the air from circulating between the plate and partition. Each end of the fire-box is supplied with a ribbed end piece, g, which is made concave at the inner surface, and has a rim at top to prevent its fitting close to the fire-box. The end pieces g have numerous perforations for the passage of air received through holes made in the external casing of the stove.

By the above-described devices it will be seen that currents of air will be received into the fire-box from the rear and ends as well as from beneath the grate, and thus combustion greatly promoted. It will be remarked that the end pieces g are adjustable, and when burnt out can be removed and others put in their place.

Having thus described my invention, what I claim, and desire to secure by Letters Patent, is—

1. The grate furnished with the convex rim t, constructed as and for the purpose herein set forth.
2. The adjustable flanged and perforated ribbed end pieces g, constructed in the manner herein described.
3. The combination of the rim t, the end pieces g, and rim e, the whole constructed and operating substantially as herein described.

In testimony that I claim the above as my own I hereby affix my signature in the presence of two witnesses.

PETER LOW.
